UNITED STATES PATENT OFFICE.

LOUIS WM. H. SCHIMPFF, OF NEW YORK, N. Y., ASSIGNOR TO THE KNY-SCHEERER CORPORATION, A CORPORATION OF NEW YORK.

STRANDED-CONTROL X-RAY SYSTEM.

1,260,070.

Specification of Letters Patent. Patented Mar. 19, 1918.

Application filed March 15, 1917. Serial No. 154,963.

To all whom it may concern:

Be it known that I, LOUIS W. H. SCHIMPFF, a citizen of the United States, and a resident of the city, county, and State of New York, have invented certain new and useful Improvements in Stranded-Control X-Ray Systems, set forth in the following specification.

This invention relates to X-ray systems. 10 Customarily an X-ray system is for the most part provided in a cabinet mounting the various parts of the apparatus, which in a modern system are many and varied. The object of the present invention is to simplify 15 and consequently cheapen an X-ray system while, at the same time, preserving efficiency, adjustability and maximum penetrating power for any one of various sizes of X-ray tubes which may be employed. Customarily, in order to adapt an X-ray system for 20 use with varying capacity tubes, a more or less expensive rheostat is provided for the primary circuit and in addition a primary winding is tapped off at various points and 25 connected with a regulator whereby the number of turns and circuit may be varied. These current taps give rise to much difficulty in a high potential transformer of the kind necessary for X-ray work.

30 I propose to carry out my invention by eliminating current taps for the primary and changing the primary winding into a combined rheostat and primary winding by constructing the same out of many strands of 35 resistance wire. By this expediency a simple shunting bridge may be employed to vary the number of strands of the primary winding which are connected in parallel across the source of constant potential alternating 40 current.

The above and further objects of my invention will be understood by reference to the illustrative embodiment described in the following specification and shown in the accompanying drawings, which form a part hereof, in which like characters designate corresponding parts in the several figures, and in which Figure 1 is a diagrammatic representation of my system; Fig. 2 is a 45 diagrammatic cross-section drawn to an enlarged scale of my stranded primary conductor; and Fig. 3 is a front elevation with parts broken away of a cabinet embodying my system.

50 The leads 1 indicate a suitable source of

constant potential alternating current, which is led to the reversing switch 2 and to the synchronous motor 3. The rectifying switch 4 is directly coupled to the synchronous motor 3 and operates in a usual manner to supply the high potential terminals 5 and in turn the X-ray tube 6 with pulsating high potential current. In my simplified system, all that is necessary both for stepping up the potential and control between the switch 2 and the rectifying switch 4 or between the switch 2 and the X-ray tube 6, if no rectifying switch is employed, are the parts presently to be described.

70

Intermediate parts.

A suitable core 7 of magnetic material is provided. In the illustration, a core having a closed magnetic circuit is indicated, but it is not desired to limit the invention to a closed magnetic circuit core. Upon this core is wound the desired number of turns of a primary winding 8. This primary winding is a conductor built up of a suitable number of individual conducting strands 9, each 80 having insulation 10, insulating it from its neighbor and from the core. In the embodiment illustrated there are ten (10) strands preferably formed out of resistance wire such as German silver wire or copper strands 85 of proper length and gage. One end of each strand is connected to a contact 11, the contacts 11 preferably being arranged in a circle as a part of the regulator R mounted on the side of the cabinet S. The other 90 ends of all the strands 9 are connected to a common lead 12 extending to the reversing switch 2, the other pole of which switch is connected by the lead 13 to the conducting bridge 14 which is rotated about the pivot 95 15 by the handle 16 of the regulator R.

A wall of insulation 17 preferably surrounds the primary winding 8 and about this insulation is wound a secondary winding T, which is shown comprising four (4) coils 100 18, 19, 20 and 21. The entire transformer structure V is preferably contained in an oil tank W.

What I claim and what I desire to secure by United States Letters Patent is:

105 In an X-ray system an X-ray tube; a source of constant potential alternating current; and combined means for stepping up the potential of said source and for regulating the quantity of current for said X-ray 110

tube comprising a core of magnetic material, a primary winding of mutually insulated strands of resistance wire, a plurality of contacts one for one end of each said strand, a common terminal for all the opposite ends of said strands, a conducting bridge for progressively shunting said contacts, and a high-potential secondary winding on said

core for supplying said X-ray tube whereby both a regulating rheostat and taps out of a 10 primary winding are eliminated from the system and full regulation is provided.

In witness whereof I have signed my name to this specification, this 12th day of March, 1917.

LOUIS WM. H. SCHIMPFF.
